(57) **CLAIM**

The ornamental design for a digital night vision monocular, as shown and described.

DESCRIPTION

FIG. 1 is a first perspective view of a digital night vision monocular showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 2.

The evenly dashed broken lines in the drawings depict portions of the night vision monocular that form no part of the claimed design. The long dash-short dash broken lines in the drawings demarcate the boundaries of the enlarged views and form no part of the claimed design.
